Application February 15, 1938, Serial No. 190,650
 In Germany February 20, 1937

5 Claims. (Cl. 60—52)

This invention relates to hydraulic power systems and more particularly to apparatus comprising a plurality of pumping units which, in combination, are adapted to give a wide range of fluid pressures and fluid outputs.

Quite frequently in instances where a servomotor is used to overcome some resistance, said resistance varies in magnitude over a wide range, as, for example, in the actuation by a servomotor of the collapsible landing gear of an airplane. It is well known that, in order to retract the carriage of an airplane, it is necessary to apply a relatively low pressure during the greater part of the retraction and a comparatively high pressure at the very end of the retraction, and, if a single pump driven by an electric motor provides the fluid to the servomotor, the pumping unit, including the pump and electro-motor, must be designed to meet the maximum demand of the servomotor, i. e., the demand at the end of the retraction. As a result, the pumping unit operates at full load only during a fractional part of the total time that it is used. It is accordingly an object of the present invention to provide a novel hydraulic power unit which is adapted for use with a servomotor demanding varying fluid pressures and which comprises a plurality of pumps, each of which operates at substantially full load for all pressure outputs of the unit, thereby saving weight and space over a pumping unit comprising a single pump operating under similar load conditions. The decreased weight and size of the former is due to the difference in capacity of the electric motors necessary to drive the said power units.

Another object of the invention is to provide a novel power means for procuring either a low fluid pressure with a large fluid output or a greater fluid pressure with a decreased output.

A further object of the invention is to provide a novel automatic means for controlling the output of the above power unit in accordance with the pressure demand thereon.

Still another object is to provide a novel hydraulic power unit which is particularly adapted for actuating the retractable landing gear of an airplane.

A still further object is to provide a novel supplementary feeder in combination with the above hydraulic power means for the purpose of meeting any excessive demands for fluid pressure or fluid output upon said means.

The above and further objects and novel features of the invention will more fully appear

from the following description when the same is taken in connection with the accompanying drawing. It is to be expressly understood, however, that the drawing is for the purpose of illustration only and is not intended to define the limits of the invention, reference for this latter purpose being had primarily to the appended claims.

In the drawing, wherein like reference characters refer to like parts throughout the several views—

Fig. 1 is a pressure curve showing the pressure demand upon the servomotor of a retractable landing gear during the collapsing of the carriage, and

Fig. 2 is a diagrammatic representation of one embodiment of the present invention.

In the single embodiment of the invention illustrated in the drawing, there is provided a hydraulic power unit comprising a plurality of fluid pumps and a pressure responsive valve mechanism for controlling the fluid connection between the said pumps. The pumps are connected, depending upon the desired pressure output, either in parallel or in series, i. e., either as a group of single stage pumps operating between the same pressure range or as a single pump comprising several stages operating between a greater pressure range. When the power unit is used, as, for example, to feed a servomotor, the pumps initially operate in parallel, pumping a large quantity of low pressure fluid, but when the pressure demand reaches a predetermined value, preferably when the pumps become slightly overloaded, the valve mechanism controlling the connections between said pumps automatically rearranges said connections to cause the pumps to operate in series and the increased pressure demand is readily met, although the fluid output is proportionately decreased. A supplementary feeder and a valve mechanism controlling the operation thereof are also provided and are adapted to supply fluid to the motor, upon a drop of pressure when the pumps are operating in either pressure range or in the alternative to supply fluid to the pump intake upon a predetermined pressure rise, when the pumps are connected in series.

The pressure demand upon the novel hydraulic power system of the present invention by the servomotor of a retractable landing gear unit, as shown in Fig. 1, is typical of the conditions under which said system operates most efficiently. When the carriage is to be retracted, the pressure during the greater part of the

retraction does not exceed p . However, after the gear has been moved into the airplane body, the pressure must necessarily be increased to terminally move the landing gear into full retracted or housed position and during this part b of the retraction, the pressure builds up considerably in excess of p . If the pressure exceeds that of the pumps operating in series and the demand is for a still greater fluid pressure, the valve mechanism controlling the supplementary feeder is automatically operated to introduce the said feeder into the fluid circuit to meet the demand.

In the embodiment illustrated in Fig. 2, the novel power system comprises a reservoir or source 4, from which fluid is adapted to flow into a conduit 5 and through a valve mechanism 6 into the fluid circuit of the said system. Normally, conduit 5 is directly connected by valve mechanism 6 with a conduit 7 and, when the power system is operating in the low pressure range, i. e., below pressure p , substantially one-half of the fluid flows from conduit 7 to a conduit 8. The latter, as shown, is connected to the suction port of a rotary pump 9, diagrammatically illustrated in the drawing. It will be understood that pumps 9 and 17 are of the type in which an increase in the input pressure will cause a corresponding increase in its output pressure. Pump 9 is preferably driven by an electric motor (not shown) and the high pressure fluid discharge therefrom flows into a conduit 10 and from said conduit through a control valve mechanism 11, then through conduits 12 and 13 to a conduit 14.

A conduit 15, by which substantially one-half of the fluid flow through conduit 7 from source 4 is diverted when the system is operating in the low pressure range, causes the diverted portion of the fluid to pass through valve mechanism 11 and into a conduit 16. Conduit 16 is connected to the suction port of a pump 17, which is of a similar design to pump 9 and which is preferably driven by the same electric motor as pump 9. The discharge from pump 17 flows into conduit 14 where it combines with the high pressure discharge of pump 9, and the combined discharge of the two pumps flows into a servo-motor 18 to drive a piston 19 and operate, for example, the retractable landing gear of an airplane. When operating in this manner, the combined discharge of the pumps is the sum of the fluid outputs of each of the pumps and the pressure of said discharge is equal to the pressure which a single pump is capable of producing.

When the resistance to the movement of piston 19 increases to the point where the demand upon the pumps is for a fluid pressure equal to or greater than pressure p , the resulting increase in the pressure discharge of the pumps in response to this demand actuates valve mechanism 11 and causes said mechanism to shut off conduits 10 and 16 from conduits 12 and 15, respectively, and to connect the two first-named conduits to each other. The rearrangement of connections is preferably effected by movement of a piston valve 20 in a casing or valve body 21 of valve mechanism 11. As shown, said valve is adapted for reciprocal movement in said body and is normally maintained in a position to permit fluid flow from conduit 10 to conduit 12 and from conduit 15 to conduit 16 by suitable resilient means in the form of coil spring 22 interposed between said body and the right end of said valve. A chamber 23 between said body and the

left end of said piston valve is connected by channel 24 to the conduit 10 and, therefore, to the discharge side of pump 9 and when the pressure in said chamber becomes great enough to overcome the resistive force of spring 22, valve 20 is moved thereby to the right and simultaneously shuts off the connection between conduit 16 and conduit 12 and between conduit 15 and conduit 16 and opens a connection between conduit 10 and conduit 16. Coil spring 22 may be suitably chosen so as to have the above movement occur in response to any predetermined pressure and in the instance where the power system is utilized in combination with a retractable landing gear, the rearrangement of connections between pumps 9 and 17 is made to occur when the demand begins to exceed the pressure p . The said rearrangement of connections causes pumps 17 and 9 to operate in series instead of, as initially, in parallel and the discharge fluid of pump 9 now feeds the suction intake of pump 17 providing a two-stage pumping system which has an initial second stage pressure equal to the final pressure of the pumping unit when operating in parallel.

In addition to the above-described means for producing an increase in pressure, a supplementary feeder 25 is shown in the illustrated embodiment as connected in the fluid circuit to meet any sudden demands for an increased pressure or for an increased fluid output in either operating range of pumping units 9 and 17. During the normal operation of the power system, said feeder is connected to the high pressure or discharge side of said pumping units by conduits 26 and 27. Conduit 26 is connected at one end to the junction of conduits 12 and 13 and at the other end to valve mechanism 6, and conduit 27 is connected from said valve mechanism to said supplementary feeder. Feeder 25 comprises a piston 28 reciprocable in a cylinder 29 and means, in the form of coil spring 30, interposed between the right end of said cylinder and the right face of said piston, tending to keep said piston from movement to the right. As a result, the fluid capacity of the left end of said cylinder is a function of the pressure of the fluid flowing therein through conduit 27 and when the pressure of the pump discharge fluid in conduit 14 is equal to the pressure of the fluid within said cylinder end, there is no flow into or out of said cylinder through the conduit 27. However, any increase in the discharge pressure causes a flow into cylinder 29 and correspondingly any sudden decrease in pressure in the discharge of the pumps due perhaps to a greater demand upon the fluid output thereof causes a flow of fluid out of said cylinder. Therefore, in normal operation, whether in the high or low pressure range, supplementary feeder 25 may act to offset any sudden demand upon the fluid volume output of pumps 9 and 17.

A further increase of the pressure output of the hydraulic power system during operation in the high pressure range may be had by suitable operation of valve mechanism 6 in conjunction with supplementary feeder 25. This is accomplished by charging said feeder as above described and causing the pressure in said feeder to become equal to the discharge pressure of said pumps. Then, if a further pressure demand is made upon said pumps, valve mechanism 6 may be so designed as to respond to the increased

discharge pressure built up by the pumps to meet this increased demand, and automatically cut off conduits 5 and 26 from conduits 7 and 27, respectively, and opens conduit 27 to conduit 7, thereby feeding the suction side of pump 9 with a fluid of a pressure equal to the discharge pressure of said pumps at the time valve 6 is operated and thereby increasing the operating range of said pumps.

Thus, when operating to give the greatest possible pressure range, the hydraulic power unit operates with pumps 9 and 17 connected in parallel and fed by the fluid from source 4 and with supplementary feeder 25 being charged by the discharge fluid of said pumps. Upon any sudden decrease in output pressure, due to sudden demand, feeder 25 will supply the pumps, as was described above. If the pressure demand continues to increase and reaches the higher operating range, i. e., the range above p (Fig. 1), the valve 20 of valve mechanism 11 is actuated by the increased pressure of the pump to meet this demand and rearranges the connection between said pumps, connecting the same in series as previously described in detail. As the multi-stage operation of pump units 9 and 17 begins, valve mechanism 6 is so chosen that the fluid circuit is fed by source 4 and supplementary feeder 25 is charged by the high pressure discharge of pumps 17 and 9 in series and the same will continue to be so charged until a still further pressure demand brings said feeder into the fluid circuit to feed the suction side of pump 9 and thereby increase the discharge pressure of pumps 17 and 9 in series. The last step is performed as follows:

Referring to the valve 6 of Fig. 2 and assuming that a pressure slightly above the minimum output of pumps 9 and 17 in series is required by servomotor 18. The discharged pressure of the two pumps at this value will be lead by conduit 26 through the port 33 in piston 32 to chamber 34. This pressure will be exerted against piston 32 to move the same to the right against the force of spring 31. The connection between conduits 5 and 7 is not broken, however, until conduits 27 and 7 are connected by the shift of the piston 32. At this time the pressure in chamber 34 forces the piston 32 to shut off the communication of conduit 5 so that source 4 no longer feeds the pumps. An initial pressure slightly above the minimum pressure of the pumps in series is then fed from the feeder 25 by way of conduits 7 and 27 to the inlet of pump 9.

There is thus provided a novel hydraulic power system which is adapted, for example, for actuating the retractable landing gear of an airplane and which, as a complete unit, weighs less than the pumping unit, at present employed in airplanes for this purpose. There is, furthermore, provided a novel arrangement of a plurality of pumps, a supplementary feeder, and novel automatic control means therefor, whereby a wide range of pressure outputs may be obtained during substantially full load operation of the pumps.

Although only a single embodiment of the invention has been illustrated and described in detail, it is to be expressly understood that the same is not limited thereto. For instance, though only two pumps are shown in the illustrated embodiment, it is understood that any greater number might be utilized without departing from

the spirit and scope of the invention. For a definition of the limits of the invention, reference will be had primarily to the appended claims.

5. What is claimed is:

1. In apparatus of the class described, a servomotor, a plurality of pumps in parallel, a conduit connecting said pumps to said servomotor, valve mechanism operatively controlled by the discharge pressure of one of said pumps and adapted to change the fluid connections between said pumps causing a series arrangement of the latter, a reservoir of fluid, a second conduit connecting said reservoir to said pumps, valve means controlling the fluid flow through said second-named conduit, and a supplementary feeder normally connected through said valve means to said first-named conduit and adapted to be disconnected therefrom by said valve means at a predetermined pressure output of said pumps whereupon said feeder is placed in communication with said second-named conduit.

2. In apparatus of the class described, a fluid reservoir, a plurality of pumps fed from said reservoir, conduit means connecting said pumps to act in parallel, a servomotor fed by said pumps, means in the discharge end of one of said pumps operative to cause a series arrangement of said pumps when the pressure in said discharge reaches a predetermined amount, and means connected in the discharge end of said pumps whereby upon a further increase in pressure in the discharge end of said pumps the latter are disconnected from said fluid reservoir and the pressure input at the inlet of said one pump is increased.

3. In apparatus of the class described, a fluid reservoir, a plurality of fluid pumps arranged in parallel and being normally fed from said reservoir, means comprising a valve responsive to the pressure demand upon said pumps for increasing the pressure output thereof by varying the connection of said pumps to a series arrangement, and means for further increasing the pressure output of said pumps, said last-named means comprising a supplementary feeder normally fed by the output of said pumps and a valve mechanism interposed in the output of said pumps and operative when the pressure in the pump output reaches a predetermined amount to disconnect said pumps from said fluid reservoir and to connect said feeder with the input of the first of said pumps when the latter are in series arrangement.

5. In apparatus of the class described, a fluid reservoir, a plurality of fluid pumps arranged to operate in parallel and fed from said reservoir, means responsive to the pressure demand upon said pumps for increasing the pressure output thereof by varying the connections of said pumps from a parallel to a series arrangement, a supplementary reservoir in the output side of said pumps normally fed by said pumps, and valve means connecting said last-named reservoir to the output side of said pumps whereby upon a predetermined increase in the pressure in the output side of said pumps said valve means act to cut off said pumps from said first-named reservoir and to place said last-named reservoir in communication with the input of the first of said pumps when the latter are in series arrangement.

5. In apparatus of the class described, a servomotor, pumping means adapted to operate in

parallel, a conduit connecting said pumping means to said servo-motor, a pressure controlled valve operatively connected to said pumping means and adapted to change the fluid connections to a series arrangement for said pumping means, a fluid reservoir, a second conduit connecting said reservoir to said pumping means, valve means controlling the fluid flow from said

reservoir, and a supplementary feeder connected to said second-named conduit through said valve means, said valve means operating upon the attaining of a predetermined pressure in the second-named conduit to cause said feeder to supply said reservoir as a fluid source.
